CLAIM

The ornamental design for a display screen portion having a graphical user interface with an animated icon of a tympanic membrane mobility scale, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen portion having a graphical user interface with an animated icon of a tympanic membrane mobility scale showing a first image in a transitional sequence according to the claimed design;

FIG. 2 is a second image thereof;

FIG. 3 is a third image thereof;

FIG. 4 is a fourth image thereof; and,

FIG. 5 is a fifth image thereof.

The broken lines in the figures show a display screen or portion thereof and form no part of the claimed design.

The appearance of the animated images sequentially transitions between the images shown in FIGS. 1-5 in a first embodiment and between the images shown in FIGS. 5-1 in a second embodiment. The process or period in which one image transitions to another forms no part of the claimed design.

1 Claim, 5 Drawing Sheets
(5 of 5 Drawing Sheet(s) Filed in Color)
